UNITED STATES PATENT OFFICE.

WILLIAM EVANS COLWELL, OF ZION CITY, ILLINOIS.

FUEL-OIL BURNER.

1,120,446.

Specification of Letters Patent.

Patented Dec. 8, 1914.

Application filed April 4, 1914. Serial No. 829,446.

To all whom it may concern:

Be it known that I, WILLIAM EVANS COLWELL, a subject of the King of Great Britain, residing in Zion City, in the county of Lake, State of Illinois, one of the United States of America, have invented certain new and useful Improvements in Fuel-Oil Burners, of which the following is a specification.

10 My invention relates to improvements in fuel-oil burners, and relates more particularly to that type of fuel-oil burner designed to be used in the fire box of an ordinary cookstove, though of course my invention may be applied to fuel-oil burners designed for other uses.

The principal objects of my invention are: firstly to provide means intermediate the generating tube and the burner to remove foreign matter such as dust and scale from the gas; secondly to provide regulating means in the mixing tube whereby the amount of air required to mix with the gas may be regulated at will; thirdly to provide means to cut off portion of the burner when it is desirous of concentrating the flame in a particular place and so save consumption of oil, and, fourthly to so mount the burner that the same may be adjusted 25 on its longitudinal axis in order that the oven may be quickly heated when desired, and the construction of my invention will be hereinafter particularly set forth and what I claim as new will be pointed out in 30 the claims forming part of this specification.

Figure 1 is a side elevation of my fuel-oil burner, (portion being shown in section to illustrate internal construction), 40 the same being shown mounted in the fire box of an ordinary kitchen range which is shown in section. Fig. 2 is an elevation of the outer end of my burner, showing the same mounted in a fire box which is shown in cross section. Fig. 3 is a detail view of the trap hereinafter referred to, portions thereof being shown in section. Figs. 4 and 45 5 are vertical cross sections respectively on the lines 4-4 and 5-5 Fig. 1, and Fig. 6 50 is a vertical longitudinal section through one end of the burner on the line 6-6 Fig. 2.

In the drawings like characters of reference indicate corresponding parts in each figure.

A is the fire box of an ordinary cook-

stove in which my fuel-oil burner is designed to be suitably mounted. The fuel-oil burner comprises any suitable generating tube B, the extension C of which extends through the wall D of the stove. E is the oil intake pipe, and the same is coupled to the extension C by the valve casing F. G is the needle valve which controls the supply of fuel oil to said generating tube B. The extension 2 of the generating tube B screws into the head 3 of the trap 4.

5 is a coupling screwing into the head 3. This coupling 5 extends through the wall D and is connected with the gas pipe 6 by the 70 elbow coupling 7.

8 is the mixing tube which extends through the wall D. This mixing tube is provided with an elbow coupling 9 in the return end 10 of which is adjustably mounted 75 the burner 11.

Any of the well known methods are employed to initially heat the generating tube. The gas passes from this tube through the connections already described into the gas 80 pipe 6, and passes through the elbow coupling 12 in to the gas nipple 13 which extends through the outer end of the mixing tube 8. The outer end of the gas nipple 13 is closed by a cap 14, and the outer end 85 of the mixing tube 8 is closed by a cap 15. The gas escapes from the gas nipple 13 through the orifice or small hole 16 and shoots into the mixing tube 8. As this mixing tube is provided with a hole 17 in its 90 outer end positioned outside of the fire box, the stream of gas escaping from the gas nipple 13 draws in the required amount of air. As the burner 11 is provided with the usual slots 18, the gas escapes through the 95 same and is consumed, and heats up the generating tube B.

Many of the parts already described are of course well known. One of the objects of my invention is to provide means for regulating the amount of air passing into the mixing tube 8 through the hole 17. My construction for this purpose comprises a sleeve 19 mounted on the end of the mixing tube 8 which projects through the wall D, 100 and formed in the sleeve 19 is an opening or a hole 20 substantially the same size as the hole 17, and positioned to be moved into alignment therewith. By means of the lug 21 carried by the sleeve 19, this sleeve can be 105 adjusted so as to regulate the quantity of air passing through the hole 17. This

means of regulating the volume of air passing into the mixing tube is very simple in construction, and the position thereof is very convenient.

5 Another object of my invention is to remove the dust, scale and other foreign matter from the gas as it leaves the generating tube in order to prevent the clogging up of the orifice 16. Integrally formed with the 10 head 3 of the trap 4 is a depending baffle lug 22, the lower end 23 of which preferably extends below the top opening 24 of the hollow pillar 25. The gas escaping from the extension 2 impinges against the side 26 of the baffle lug 22, and as this side of the 15 said lug is preferably concaved as illustrated in Fig. 3, the stream of gas is deflected downward, with the result that whatever particles of foreign matter may 20 be carried along with the gas will be caused to drop down into the pillar 25 and collect in the lower portion thereof. The gas of course ultimately escapes from the trap 4 through the end 27 of the head 3.

25 28 is a screw cap closing the end of the pillar 25. This cap may be removed when desired to permit the said pillar to be cleaned.

By positioning the lower end 23 of the 30 lug 22 as described, I prevent the particles of foreign matter carried along by the gas into the head 3 being carried thereout of by the gas.

One end of the burner 11 is closed by a 35 plug 29, and suitably secured in this plug, by screw thread or otherwise is a rod 30, which is locked in place by the nut 31 when said rod is threaded. This rod is provided at its outer end with a cross bar 32. The 40 inner end 43 of the burner 11 is adjustably mounted within the return end 10 of the elbow coupling 9. By means of the cross bar 32 and the construction just described, the burner 11 may be turned on its longitudinal axis so as to adjust the position of the flame in respect of the back wall 33 of the fire box A. The slots 18 are preferably 45 formed in the burner 11 in two rows down each side thereof, as illustrated in Fig. 5. 50 Without further explanation it will be understood that when the burner 11 is turned on its axis to the right, the said slots will be positioned so that the burning gases will play against the back wall 33 and so heat the oven which is behind said back wall (but not shown in the drawings) much quicker than when the slots 18 are positioned as 55 illustrated in Figs. 1 and 5. This adjustment of the burner 11 is very important.

60 Mounted on the burner 11 to be moved longitudinally thereof as well as circumferentially, is a burner cut off, in the form of a sleeve 34 provided at each end with a loop or ring 35, whereby it is mounted on the 65 burner 11. The said loops or rings are con-

nected by a tie bar 36, which is normally positioned at the top side of the burner 11. The sleeve 34 is provided down each side with a longitudinal slot 37, the lower edge 38 of which is on a level with the bottom 70 ends of the slots 18.

75 39 is the cut off portion of the sleeve 34, and the same is substantially semicircular in cross section and is imperforate. By means of the lug 40, the sleeve 34 may be moved longitudinally on the burner 11 and then the cut off 39 may be moved to close a certain number of the slots 18 in the burner 11, and thus prevent lighted gas from issuing therefrom. The object of the burner 80 cut off is to concentrate the heat under, for example, the hole closed by the stove lid b. In the position of the cut off 39 illustrated in Fig. 1, heat is playing against the lids b and c. The said cut off enables heat to be 85 concentrated underneath either of the openings controlled by the said lids with obvious advantages.

The sleeve 34 is substantially one-half the length of the heat generating length of the 90 burner 11.

I may use any suitable means for performing the function of the burner cut off already described.

Various changes in construction may be 95 made in that illustrated and described without departing from the spirit of my invention.

What I claim as my invention is:

1. In a fuel-oil burner, the combination 100 with a generating tube; a mixing tube, and a burner, of a trap intermediate said generating tube and said mixing tube in the form of a hollow pillar provided in its head with a downward depending baffle lug against 105 which the stream of gas impinges as it passes from said generating tube into said mixing tube, as set forth.

2. In a fuel-oil burner, the combination 110 with a generating tube; a mixing tube, and a burner, of a trap intermediate said generating tube and said mixing tube in the form of an open end hollow pillar provided in its head with a downward depending baffle lug against 115 which the stream of gas impinges as it passes from said generating tube, and a screw cap closing the open end of said pillar, as set forth.

3. In a fuel-oil burner, the combination 120 with a generating tube; a mixing tube, provided in its outer portion with an intake hole for the air; a gas nipple connected with said generating tube and extending transversely through the outer end of said mixing tube and provided with a gas orifice, 125 and a burner, of a sleeve provided with an opening or hole mounted on the outer end of said mixing tube, and means whereby the position of said sleeve is adjusted to regulate the volume of air passing into said mix- 130

ing tube through the hole therein, as set forth.

4. In a fuel-oil burner, the combination with a generating tube, and a mixing tube, of a coupling carried by the inner end of said mixing tube; a burner movably mounted in one end of said coupling, and means carried by the opposite end of said burner whereby the said burner may be adjusted 10 on its longitudinal axis.

5. In a fuel oil burner, the combination with the burner proper, of a burner cut-off in the form of a sleeve mounted to be moved longitudinally and circumferentially on 15 said burner, and provided with a slot down each side thereof, to form a loop at each end

of the cut-off, and a centrally positioned tie bar connecting said loops together; the said slots circumferentially being co-extensive with the slots formed in said burner, and extending in an unbroken form throughout their length; the lower portion of said sleeve being the cut-off proper, and constructed substantially semicircular in cross section, as set forth.

20 In testimony whereof I have affixed my signature in presence of two witnesses.
